UNITED STATES PATENT OFFICE.

GEORGE A. FREDENBURGH, OF PAWTUCKET, RHODE ISLAND.

BRUSH-CYLINDER FOR THREAD-DRESSING MACHINES.

SPECIFICATION forming part of Letters Patent No. 746,946, dated December 15, 1903.

Application filed May 18, 1903. Serial No. 157,721. (No model.)

To all whom it may concern:

Be it known that I, GEORGE A. FREDENBURGH, a citizen of the United States, residing at the city of Pawtucket, in the county of Providence and State of Rhode Island, have invented certain new and useful Improvements in Brush-Cylinders for Thread-Dressing Machines, of which the following is a specification.

10 This invention relates to a brush-cylinder adapted for a thread-dressing machine.

The invention consists in the combination of a stationary steam-pipe mounted in proper supports on the machine-frame, a tubular shaft surrounding said steam-pipe, a roller-cage secured upon each end of said tubular shaft, a cylindrical tube surrounding said tubular shaft and divided longitudinally into halves, each half of said tube provided with 20 bristles upon its exterior surface, means for locking the two halves of said tube to the said tubular shaft, and means for rotating said brush-cylinder, all as hereinafter described, and specifically set forth in the claims.

25 In the accompanying sheet of drawings, Figure 1 represents a central longitudinal sectional view of my improved brush-cylinder for a thread-dressing machine. Fig. 2 is a longitudinal elevation view of one of the 30 halves of the brush proper. Fig. 3 is an end elevation view of Fig. 2. Fig. 4 is a cross-sectional view taken in line X X of Fig. 2.

Fig. 5 is an enlarged longitudinal section of a portion of the brush-cylinder and its parts, 35 taken in line Y Y of Fig. 1. Fig. 6 is a cross-sectional view of the brush-cylinder, taken in line Z Z of Fig. 1. Fig. 7 is a front elevation of the roller-cage, and Fig. 8 is a side elevation of the same.

40 Like letters indicate like parts.

A A represents a portion of the machine-frame, upon which brackets or supports B B have each a box d, provided with a cap e, which is secured to each box by bolts f f, 45 that enter threaded openings f' f', as seen in Fig. 5. A steam-pipe g is mounted in the boxes d, and a set-screw h, which enters through the caps e of the said boxes, serves to hold the said pipe in a fixed position in 50 the manner shown in Fig. 5. A tubular shaft i loosely surrounds the steam-pipe g

between the brackets or supports B B and has each end circumferentially screw-threaded.

j j are two circular sleeves, each of which has a portion of its interior surface screw-threaded to receive the threaded ends of the tubular shaft i, and each of said sleeves is firmly secured to said shaft by dowel-pins, as indicated at k k in Fig. 5.

C is the brush-cylinder proper, comprising 60 a hollow wooden tube which is divided longitudinally throughout its length into halves l l, and each half of said brush is provided with bristles m m, secured upon its exterior surface in any suitable manner. Each of the 65 wood halves l l of the cylinder C has a series of semicircular metallic flanged strips n n, which are located in alignment with each other and are rigidly secured to the said halves l l by bolts o o, as shown in Figs. 1, 2, and 4. 70

n' n' are a series of rings made fast upon the shaft i, and each of these rings has an outer lateral annular flange arranged to fit over the inner lateral flange of each of the strips n n, and thus forming a means for 75 uniting or locking the halves of the brush C together, and in order to have the brush-halves l l turn with the shaft i the keys k' k' (shown in dotted lines in Fig. 5) project a sufficient length beyond each series of rings 80 n' to enter a groove n², (see Fig. 2,) formed in each of the flanged strips n of the brush-halves.

Circular disks p p are mounted upon the shaft i, and each disk has a laterally-projecting annular flange p' to close over the ends of the halves l l when locked together as described. The ends of the halves l l are secured to the disks p p by screws which pass through the annular flanges of the same, as 90 seen in Fig. 1.

In the space formed in the sleeves j j at each end of the shaft i is mounted a roller-cage (see Figs. 7 and 8) comprising two rings q q, between which a series of rollers q' q' are 95 rotatably mounted. This cage when in position at each end of the cylinder is arranged to have its rollers revolve upon the surfaces of the sleeves j j and steam-pipe g, respectively. This brush-cylinder, constructed as 100 described, is rotated upon the stationary steam-pipe g by means of a spur-gear r, which

is keyed to one of the sleeves *j*, and said gear *r* meshes with another gear *r'*, which receives power from the main or driving shaft of the machine. This brush-cylinder is adapted to 5 lay the projecting fibers of the thread as the thread comes up from the sizing-box, (not shown,) and in order to have all the fibers laid straight the cylinder must revolve at a very high rate of speed, so that by having the 10 brush portion of the cylinder made in halves and locked together, as described, the high speed required can be maintained without the danger of breakage, as happens occasionally in the use of wood strips or lagging 15 in the construction of the ordinary brush-cylinder. Furthermore, by having my improved brush-cylinder provided with suitable rollers the friction caused by the speed of rotation is much lessened.

20 This invention is an improvement upon the thread-dressing machine shown and described in Letters Patent of the United States No. 702,786, issued to me June 17, 1902.

I claim as a novel and useful invention and 25 desire to secure by Letters Patent—

1. In a thread-dressing machine having two brackets or supports fixed to the frame thereof, said supports having bearing-boxes, and a steam-pipe fixed in the boxes of said supports, the combination therewith, of a brush-cylinder, comprising a tubular shaft loosely 30 surrounding the said steam-pipe and having

a series of flanged rings rigidly secured upon its exterior surface, a roller-cage mounted on each end of said shaft, a wooden tube divided 35 longitudinally into halves, each half of said tube provided with bristles secured in its peripheral surface, a series of semicircular flanged strips rigidly secured upon the interior surface of each of the halves of said tube 40 and arranged to engage by their flanges with the flanges of said rings in holding the two halves of said tube together upon said shaft, substantially as set forth.

2. In a thread-dressing machine having a 45 stationary pipe mounted in supports of the machine-frame, the combination, of a brush-cylinder, comprising a tubular shaft loosely surrounding the said pipe, a roller-cage properly mounted upon each end of said shaft, a 50 wood tube divided longitudinally into halves and provided with bristles secured upon the peripheral surface thereof, means for locking the halves of said tube to said shaft, and a gear rigid upon said shaft and arranged to 55 receive power to rotate said brush-cylinder, substantially as set forth.

In testimony whereof I affix my signature in the presence of two witnesses.

GEORGE A. FREDENBURGH.
